G. LEWINNEK

COMMUTATOR

Filed Jan. 4, 1926

Inventor:
Georg Lewinnek,
by *Myron S. Jones*,
His Attorney.

UNITED STATES PATENT OFFICE.

GEORG LEWINNEK, OF BERLIN, GERMANY, ASSIGNOR TO GENERAL ELECTRIC COMPANY, A CORPORATION OF NEW YORK.

COMMUTATOR.

Application filed January 4, 1926, Serial No. 79,066, and in Germany January 22, 1925.

My invention relates to commutators for dynamo-electric machines and particularly to the construction of a double commutator. Where it has been necessary to make the commutator of considerable length, it has been found desirable to divide the bars intermediate their ends so as to form in effect two series of bars separated by spaces for cooling air. The bars of each series have had their dovetails clamped by separate sets of clamping rings and separate bolts. After the winding had been connected to the bars it was difficult to get at the securing bolts of that part of the commutator which was next to winding to tighten the same when any looseness occurred. An object of my invention therefore is to provide an improved construction of double commutator wherein this difficulty is obviated.

My invention will be better understood from the following description taken in connection with the accompanying drawing, and its scope will be pointed out in the appended claims.

In the single figure of the drawing, which is a fragmentary cross-sectional view of a commutator embodying my invention, the body 1 of the commutator has the two wedge-shaped rings 2 and 3 with which co-operate the adjustable wedge-shaped rings 4 and 5 respectively to clamp the dovetails of the two series of commutator bars 6 and 7. Single through-bolts 8 serve to clamp the two adjustable rings 4 and 5 against the two series of commutator bars. The end portions 9 of the bolts 8, which correspond to the winding end of the commutator, are of reduced diameter and the shoulder 10 on each bolt is adapted to engage a shoulder 11 on the body 1 where it passes therethrough. Nuts 12 and 13 at opposite ends of the bolts 8 engage the respective rings 4 and 5.

When the double commutator is being assembled, that half of the commutator which is next to the winding shown at the right in the drawing, is assembled first and the ring 5 is drawn up by the nut 13, the shoulder 10 on the bolt acting as a head. Subsequently the other half of the commutator may be assembled, the ring 4 being drawn up by the nuts 12 on the larger ends of the bolts 8. These nuts are always accessible even after the winding has been connected to the commutator and should any looseness occur in the bolts at their smaller ends or in the bars held thereby, it may easily be remedied by tightening these outer nuts 12. Both halves of the commutator may therefore be tightened by the same nuts.

What I claim as new and desire to secure by Letters Patent of the United States, is,

1. A double commutator comprising a body portion having a plurality of fixed and adjustable clamping rings; a double series of bars engaged thereby; clamping bolts having means engaging said body for limiting their movement in one direction; said body, said bars, and said rings being so formed that said bolts are freely removable in the other direction; and means carried by each of said bolts for clamping both series of said bars between said rings. 70
2. A double commutator comprising a body portion having a plurality of adjustable and fixed clamping rings, a double series of bars engaged thereby, clamping bolts having shoulders thereon, said body portion engaging the shoulders on said bolts for limiting their movement in one direction and being cut away so that they are freely movable in the other direction, one of said adjustable rings having openings therein through which the shoulders on said bolts are removable, and adjustable means including said bolts for clamping said rings against said bars. 85
3. A double commutator comprising a body portion having a plurality of adjustable and fixed clamping rings, a double series of bars engaged thereby, clamping bolts having shoulders thereon, said body portion engaging the shoulders on said bolts for limiting their movement in one direction and being cut away so that they are freely movable in the other direction, and means carried by each of said bolts for clamping both series of said bars between said rings. 90
4. A double commutator comprising a body portion having a plurality of fixed and adjustable clamping rings, a double series of bars engaged thereby, clamping bolts each extending through the fixed and

adjustable rings, said bolts having means engaging one of the fixed rings for limiting their movement relative thereto in one direction and being freely movable relative thereto in the other direction, and adjustable means on the ends of the bolts for engaging the adjustable rings.

5. A double commutator comprising a body portion having fixed rings, a double series of commutator bars, an adjustable ring at each end of the commutator, and a plurality of through-bolts having nuts at each end respectively engaging the adjustable rings, said bolts having shoulders engaging one of said fixed rings for limiting their movement in one direction, said fixed rings being formed so as to permit removal of the bolts in the other direction whereby one series of bars may be assembled and

clamped independently of the other series. 20

6. A double commutator comprising a body portion having a central pair of fixed rings, a series of commutator bars engaging each fixed ring, an adjustable ring at each end of the commutator, a plurality of bolts each extending through the fixed and the adjustable rings, that portion of each bolt extending through the fixed and the adjustable ring arranged at the winding end of the commutator being of reduced diameter to form a shoulder to engage one of said fixed rings whereby the series of bars at the winding end of the commutator may be assembled and clamped prior to the assembly of the other series of bars. 30

In witness whereof, I have hereunto set my hand this 10th day of December, 1925.

GEORG LEWINNEK.
